(57) **CLAIM**

The ornamental design for the combined phone holder and card wallet, as shown and described.

DESCRIPTION

FIG. 1 is a front and right perspective view of the combined phone holder and card wallet showing my new design; FIG. 2 is a rear, left, and top perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a rear, left, and top perspective view thereof but shown in use with an unclaimed phone feature; and FIG. 10 is a rear, left, and top perspective view thereof but shown in use with an unclaimed phone feature; FIG. 11 is a rear, right, and bottom perspective view thereof but shown in an alternate configuration, where a piece of card is pulled out of the wallet; and, FIG. 12 is a rear, right, and bottom perspective view thereof but shown in an alternate configuration, where the kickstand is folded.

The broken lines in the drawings depict portions of the combined phone holder and card wallet that form no part of the claimed design. The broken lines showing of a phone feature, in FIGS. 9-10, illustrate environmental structures that form no part of the claimed design.

1 Claim, 12 Drawing Sheets
